CLAIM

The ornamental design for a return vending machine, as shown and described.

DESCRIPTION

FIG. 1 is a front perspective view from one side of a return vending machine.

FIG. 2 is a front view of the return vending machine shown in FIG. 1,

FIG. 3 is a rear view of the return vending machine,

FIG. 4 is a side view of the return vending machine from one side,

FIG. 5 is a side view of the return vending machine from the other side,

FIG. 6 is a top view of the return vending machine; and,

FIG. 7 is a bottom view of the return vending machine.

The return vending machine is suitable for use in handling empty beverage packaging.

No claim is made to the subject matter shown in broken lines in the drawings.
